UNITED STATES PATENT OFFICE.

SAMUEL S. WYER, OF COLUMBUS, OHIO, ASSIGNOR, BY MESNE ASSIGNMENTS, TO THE JEFFREY MANUFACTURING COMPANY, A CORPORATION OF OHIO.

DRILL FOR ROCK, COAL, AND OTHER MATERIAL.

1,034,052.

Specification of Letters Patent. Patented July 30, 1912.

Application filed January 14, 1905. Serial No. 241,076.

To all whom it may concern:

Be it known that I, SAMUEL S. WYER, a citizen of the United States, residing at Columbus, in the county of Franklin and State of Ohio, have invented certain new and useful Improvements in Drills for Rock, Coal, and other Material, of which the following is a specification, reference being had therein to the accompanying drawing.

10 This invention relates to improvements in drill mechanisms used for drilling rock, coal and similar materials.

The improvements pertain to drills in which the work is accomplished by one or 15 more reciprocating bodies. Many of them pertain more particularly to drills of the class now commonly known as drills of the hammer type, that is, those in which the bits or cutting tools are not reciprocated by the 20 prime motor directly but have blows imparted to them through intermediate reciprocating mechanism.

Figure 1 is a vertical longitudinal section. Fig. 2 is a transverse section on line A B 25 of Fig. 1. Fig. 3 is a cross section of drill bit on line C D of Fig. 1. Fig. 4 is a cross section on line E F of Fig. 1, and shows the valve mechanism. Fig. 5 is a horizontal longitudinal section on line G H of Fig. 1. Fig. 30 6 is a cross section on line I J of Fig. 5, and shows the drill bit holder. Fig. 7 is a cross section on line K L of Fig. 5, and shows the ratchet and pawls. Fig. 8 is a side elevation of the yoke end of the driving cylinder and 35 shows the method of locking the adjusting screw. Fig. 9 is a cross section of the flexible coupling on line M N of Fig. 1. Fig. 10 is a plan view of the screened opening for admitting air to the machine. Fig. 11 is a vertical longitudinal section of the machine 40 with the motor removed and the reciprocating mechanism shown at the outer end of its path of travel. Fig. 12 is a cross section on line O P of Fig. 11, and shows the oil hole 45 for lubricating the hammer. Fig. 13 is a horizontal section on line Q R of Fig. 11. Fig. 14 is a cross section on line S T of Fig. 13, and shows the drill bit holder in position 50 to allow the removal or insertion of the drill bit. Fig. 15 is an end view. Fig. 16 is a side elevation. Fig. 17 is a cross section on the line U V of Fig. 16. Fig. 18 is a horizontal section on the line W X of Fig. 17. Fig. 19 is a plan view. Fig. 20 is a side elevation of the guide frame. Fig. 21 is a side

elevation of the shell and also shows the method of closing the drill shank hole at the lower end. Fig. 22 is a side elevation of the motor. Figs. 23, 24 and 25 are diagrams illustrating the principle and method of operation. Fig. 26 is a top plan view of the gear secured to the crank shaft for operating the drill, together with the spider and buffers by which the gear is secured to the shaft.

The prime mover is an electric motor. It is shown in Figs. 1, 16, 17, 19 and 22, and it is of the inclosed type. 1 is the frame, 2—2 represent armature bearings with bushings 3, oil cups 4 and covers 5. To facilitate the handling of the motor when it is detached from the machine, the frame is fitted with a handle 6. The power of the motor is transmitted to the drill by means of the flexible coupling shown in Figs. 1 and 9, where 7 is the armature shaft fitted with a spider 8, the latter being equipped with two rubber buffers 9. When the armature shaft revolves, the buffers bear against the shoulders 10 of the flanged rim 11 which is an integral part 20 of the pinion shaft 12 and thereby rotates shaft 12. The pinion 13 is rigidly secured to shaft 12 by means of a key 13' and the washer 14. 15 is a renewable bushing which fits into the neck of the cover 16. 17 is an oil cup with a cover 18. The pinion 13 meshes with the gear 19; 20 is the crank shaft which works in the renewable bushing 21, the latter being held in the sleeve 22. 23 is a spider which is rigidly secured to crank 25 shaft 20 and contains the rubber buffers 24. The gear 19 as shown in Fig. 2 has lugs which fit into the same annular groove that holds buffers 24 in Fig. 1. As gear 19 revolves these lugs compress the buffers 24 and thereby cause spider 23 to rotate. The object of the buffers 24 is to form an elastic connection between the gears and the crank shaft and thus reduce the danger of breakage of the gear teeth to a minimum. 25 is a collar that holds gear 19, spider 23 and buffers 24 in position. 26 is an oil chamber 30 that is supplied with oil through the valve 27 which is normally held closed by the spring 28. 29 is an oil plug that is screwed into cover 16. The cover 16 and sleeve 22 form an oil tight chamber within which the gears 13 and 19 operate. This chamber is filled with oil in order to provide proper lubrication for the gears and by opening the 35

valve 27, the oil is allowed to flow downward into the oil chamber 26. A removable plug 29 provides an opening through which oil may be poured into the casing.

5 The sleeve 22 has a tight fit in the neck 31 and is kept in alinement by the plug 32. The lower end of crank shaft 20 has a disk 33 and crank pin 34, the latter working in the sliding block or cross head 35 which reciprocates in the yoke 36 of the driving cylinder 37. The lower side of yoke 36 is covered with a steel plate 38 to keep cross head 35 from sliding off of the crank pin 34. The oil from chamber 26 flows down 10 through the openings shown and is carried out to crank pin 34, cross head 35 and yoke 36 by centrifugal force.

15 The lost motion between cross head 35 and yoke 36 is adjusted by means of the wedges 39 and 40, the latter having a nut 20 at one end in which the screw 41 works. Screw 41 has a hexagonal head as shown in Fig. 8.

20 42 is a small plunger of two diameters which is pushed out by the spring 43, the smaller diameter of plunger 42 coming out 25 and just touching the flat side of the hexagonal head of screw 41 and thereby preventing the latter from turning.

30 44 is a plug that is screwed into the shell 45. It is evident that by removing plug 44 and bringing the driving cylinder to such a 35 position that screw 41 is opposite the opening made by the removal of plug 44, that a socket wrench may be inserted over the hexagonal head, pushing back plunger 42 and then adjusting the screw 41. After the 40 requisite adjustment has been made to screw 41, it is only necessary to so turn the hexagonal head that one of its sides will be in the position shown in Figs. 5 and 8 and thus allow plunger 42 to come out and lock the head in that position.

45 The inside of the shell 45 is fitted with a renewable bronze bushing 46 in which the driving cylinder 37 reciprocates.

50 47 is an annular ring that is screwed into cylinder 37 and has a working fit on the hammer 49, the latter also has a working fit 55 on the inside of cylinder 37.

55 48 is an air cushion between hammer 49 and ring 47.

60 50 is a stop for the hammer 49 and is secured to the shell by means of the bolts 51 shown in Fig. 2. The hammer 49 has a working fit in the bushing 52 and over the drill shank 53.

65 The rotation of the hammer and drill bit is accomplished by means of the ratchet shown in Fig. 7. 54 is a feather which transmits the rotary motion of hammer 49 to drill shank 53. 55 is the pawl carrier that holds the pawls 56 and springs 57. 58 is the ratchet nut which has ratchet teeth on 65 the exterior and threads 59 on its interior,

the periphery of the hammer having threads cut on it to correspond with threads 59. 60 is a pin for holding spring 57 in position. The pawl carrier 55 is held between shell 45 and the drill head 61 by the bolts 62.

70 The drill bit holder is shown in Figs. 1, 5, 6, 11, 13 and 14. 63 is the holder plate which has a hole made by the intersection of the two sectors of circles, the smaller sector corresponding to the smaller diameter of the drill shank 53 and the other being large enough to allow the drill shank to pass through when plate 63 is moved so as to make the larger sector concentric with the drill shank as shown in Figs. 13 and 14. 75 64 is a bolt with a T-head having a sliding fit in the slot of plate 63. The spring 66 acts against the nut 65 and thus holds plate 63 and bolt 64 in the position shown in Fig. 6. To remove the drill shank 53 it is only 80 necessary to push on nut 65 and compress spring 66. 67 is an annular distance piece to keep plate 63 in position. 68 is a rubber emergency buffer that would stop the hammer 49 in case the air cushion 48 should fail.

85 The drill head 61 is fitted with a hardened steel bushing 69 which has a tight working fit on the hardened drill shank 53, the latter having an annular groove 70 cut in its 90 periphery.

95 71 is a union sleeve screwed into drill head 61 and is fitted with a female pipe union 72. The object of this connection is to admit water to, and lead it down to the 100 cutting edge of the drill bit. The water enters through the opening in sleeve 71 then passing through the slot 73 goes to groove 70 and out through the opening 74 to the tube 75 and thence down to the cutting edges of the 105 drill bit. The slot 73 is required to take care of the longitudinal movement of the drill shank 53, the amount of travel being about three eighths of an inch. Therefore, by means of groove 70 and slot 73, sleeve 71 110 can always supply opening 74 with water regardless of what the rotative or longitudinal position of the latter may be.

115 The method of attaching the motor to the machine is shown in Figs. 1, 16, 17, 18, 21 and 22, three rubber buffers being used to form the connection. 76 is a buffer, the upper end being secured to the motor frame by means of the split washer 77 and bolts 78, washer 77 being split on a diameter passing 120 through the two bolt holes. The lower end of each buffer 76 fits into a circular pocket on the machine and is held in position by the washer 79 and pin 80. The lower end of buffer 76 is of such a thickness that when 125 pin 80 is in position it compresses the larger flange or buffer 76. 80 is a pin which has a flat surface on one side adjacent to the head which allows the pin to take the position shown in Fig. 17. The pin being 130

pushed up by the pressure from the flange or buffer 76 which was compressed when the pin was driven into position. Thus the continuous upward pressure from buffer 76 prevents pin 80 from working out of place. To remove pin 80 it is only necessary to turn it through 180 degrees and it may then be easily withdrawn. By virtue of their construction and position these buffers absorb nearly all of the vibration from the striking of the drill bit and relieve the motor from the continuous shocks, thereby greatly increasing its life and efficiency.

The valve mechanism is shown in Figs. 1, 4 and 10, where 81 is a wire gauze screen over the inlet air opening 82. 83 is an outlet air chamber connected to an inner air chamber 84 by means of a puppet valve 85 which is actuated by a spring 86. Valve 85 has a long hub 87 that slides on the stem 88 which is an integral part of the piston 89 and extension stem 90, the latter having a nut 91. 92 is a valve body that is screwed into the shell of the machine and contains the piston 89 and forms the seat for valve 85. 93 is an adjusting nut that works in valve body 92 and contains the spring 94. By turning nut 93 the compression of spring 94 and the resulting pressure against nut 91 may be varied at will. 95 is a delivery chamber connected to chamber 84 by means of the puppet valve 96 which has a seat 97. 98 is a spring for actuating valve 96, the latter sliding on the spindle 99 which is an integral part of seat 97, spindle 99 and seat 97 being connected by means of ribs. 100 is a plug that is screwed into the shell 45, its object being to make the puppet valve accessible. 101 is a port connecting chamber 95 with the air chamber 106. 102 is a port connecting chamber 84 with the driving cylinder 107 shown in Figs. 11 and 13. 104 is an air chamber connecting the piston 89 with chamber 106 by means of ports 103. The operation of this valve mechanism is shown diagrammatically on sheet 5 of the drawings. The rear end of chamber 106 is closed by the plug 108. The air required to force the water to the drill bit is taken out of chamber 106 by means of the connection shown at the upper side of plug 108. 109 is a combination valve, seat and union sleeve. 110 is a valve held against its seat by the spring 111. 112 is a female pipe union. The object of valve 110 is to keep dirt out of chamber 106 when the machine is not in use.

The machine is attached to the guide frame as shown in Figs. 1, 15, 16, 17, 20 and 21. 113 is a stud that is fastened to plug 108 and has a nut 114 with a circular shoulder 115 that fits into a corresponding recess in the plug 116 which is a part of the guide frame 117. The tooth 118 is also a part of frame 117 and fits into the jaw 119 which

is an integral part of the shell 45. 120 is the feed screw nut.

The energy from the electric motor is transmitted to the hammer by means of compressed air in place of the springs that are usually used on rock drills for that purpose. The air is compressed and the pressure maintained automatically. The air chamber is quite large and the main idea is to allow the air to follow the hammer full stroke, but as the volumetric displacement of the hammer is very small in comparison to original volume of air, the decrease in pressure due to the expansion is very small. In other words, the air follows the hammer for full stroke with almost a uniform pressure.

Figs. 23, 24 and 25 are diagrams illustrating the principles and method of operation, but not details of construction.

121 is a water tank, in actual practice of about twenty gallons' capacity, which is connected to the air chamber 106 by a hose or pipe 122.

123 is a hose or pipe connecting tank 121 with the drill shank 53 and it is used for conveying the water from tank 121 to the hole in shank 53.

In the construction of the machine, pipe 122 is connected to chamber 106 by means of union 112, and pipe 123 is connected to opening by means of union 72, the flow of water to opening 74 being controlled by a needle valve 127.

Fig. 23 shows the first step in the operation. Here the driving cylinder 37, which also serves as an air pump for maintaining the air pressure in chamber 106 is just beginning its backward stroke and is drawing in air through port 102 and valve 85. The hammer 49 is also drawn back through the medium of the air cushion 48 at this stage, chamber 106 and the upper part of tank 121 are filled with air at atmospheric pressure.

Fig. 24 shows the second step in the operation. Here the driving cylinder and air pump 37 are near the end of the forward stroke, having compressed the air drawn in by the previous back stroke and forced it into the ports 101 and 103 by means of valve 96, port 103 maintaining the same air pressure back of piston 89 that there is in port 101 and chamber 106. This second step is now repeated until cylinder 37 has pumped enough air into port 101, port 103 and chamber 106 to raise the pressure to such a point that the piston 89 can compress the spring 94 and move to the position shown in Fig. 25 where the valve 85 has been unseated by piston 89. The third step now takes place, as illustrated in Fig. 25. The valve 85 being held open by piston 89 allows the air to pass in and out of port 102 at each stroke of cylinder 37 instead of being forced into port

101 and chamber 106. This step is repeated until the pressure in chamber 106, port 101 and port 103 is lowered by leakage or by the air consumption in tank 121 required to force the water out through pipe 123. Just as soon as the pressure back of piston 89 is lowered a few pounds the spring 94 will then draw piston 89 back and allow valve 85 to seat itself; and the steps illustrated by Figs. 23 and 24 will be repeated until the pressure is again raised and the steps shown in Fig. 25 will take place.

The point at which piston 89 will unseat valve 85 and thus fix the pressure to be carried in ports 101 and 103 and chamber 106 is determined by the pressure put on spring 94 by the nut 93; the latter being so arranged as to be easily adjustable. The intensity of the blow struck by hammer 49 being dependent upon the pressure carried in chamber 106, it can thus be easily varied by means of the nut 93.

In Fig. 24 the hammer has not followed cylinder 37 because the air back of hammer 49 is only at atmospheric pressure. The valve motion just described has three distinct functions; first, it acts as an automatic safety valve, second, as an automatic pressure maintainer, and, third, as an adjustable pressure regulator.

The air cushion 48 can be replaced by a rubber buffer if deemed necessary.

The machine as an entirety can be readily separated into its three component units as is shown in Figs. 17, 20, 21, and 22. To disconnect the motor it is only necessary to remove the three pins 80 and it may then be carried by the handle 6. To remove the main part of the machine from the guide frame it is only necessary to release the nut 114. 125 is a rubber plug that is inserted in the head of the drill to keep out foreign matter, which may be secured by a chain or cord if desirable. When the machine is so divided each unit is water and grit proof.

The driving cylinder 37 has the longitudinal groove 105 extending, as shown, for only a portion of its length. This groove insures that the pressure upon the rear of the hammer 49 and the buffer 47 will be equal until the forward end of the hammer head has advanced beyond the forward end of the groove, cutting off escape of air from the compression chamber 48 insuring that the compression of the air remaining therein will prevent the sudden impact of the hammer with the buffer.

The hammer 49 may be considered as having two parts, the disk-like rear end constituting a piston which is driven forward by the air acting upon its rear face, and the front socketed plunger which operates upon the tool by contact with the rear end of the drill shank. The rear end of this hammer can then be considered as an

air driven piston and also as a tool actuating piston. The front plunger end of the hammer can be considered as the tool operating means by which the energy applied to the piston is communicated to the cutting tool.

The shell 45, when considered together with the bushing 46, constitutes a motive fluid cylinder. The forward end of the driving cylinder 37 and the ring 47 constitute a piston reciprocating within the cylindrical shell 45. Functionally considered, the front end of drive cylinder 37 is a piston, and the rearwardly projecting cylindrical shell by which it is connected to the yoke and power mechanism may be considered as a kind of connecting rod. The ring 47 and front end of the driving cylinder 37, in harmony with this way of designating the above parts of the drill, can be called the first or primary and mechanically driven piston or power reciprocated part, and the rear end of the hammer 49 which has just been described as the air driven or tool actuating piston, can be called the secondary or second piston.

What I claim is:

1. The combination with a shell of a driving cylinder reciprocating therein, a drill, a drill operating means reciprocable within said driving cylinder, a rotary motor, power transmitting devices between said driving cylinder and said motor, and pneumatic connections whereby the reciprocation of said driving cylinder in said shell supplies compressed air to said drill operating means, substantially as set forth.

2. The combination with a shell of a driving cylinder reciprocating therein; a drill, a drill operating means, reciprocable within said driving cylinder, a motor, power transmitting devices between said driving cylinder and said motor, and pneumatic connections whereby the reciprocation of said driving cylinder in said shell supplies compressed air to said drill operating means, substantially as set forth.

3. The combination with a drill, of a shell, a driving cylinder for said drill and reciprocating within said shell, drill actuating means comprising a head fitted within said driving cylinder and reciprocable therein, the said shell and driving cylinder operating as an air compressor and being provided with ducts for conveying the compressed air to the interior of said driving cylinder at the rear of said head, valves for controlling the compressed air, a motor, and power transmitting means between said motor and said driving cylinder, said power transmitting mechanism comprising a crank moving in a plane parallel to the axis of said driving cylinder.

4. The combination with a drill, of a shell, a driving cylinder reciprocating within said

- shell, drill actuating means reciprocable within said driving cylinder, an air chamber within said shell and into which said driving cylinder opens at its rear end, said driving cylinder having its other end closed and adapted to coöperate with said shell to compress air therebetween, there being ducts in said shell and driving cylinder for conducting the compressed air to said chamber, 10 valves for controlling said ducts, and power transmitting devices connected with said driving cylinder, substantially as set forth. 15
5. The combination of a bit, an air driven piston for actuating it, a mechanically driven reciprocating piston adapted to retract the air driven piston on its return stroke, a cylindrical shell within which said pistons have a sliding fit and pneumatic connections whereby the mechanically driven 20 piston compresses air on its forward stroke and whereby the air thus compressed is applied to move the air-driven piston forward, the two pistons being longitudinally independent. 25
6. The combination of a drill bit, an air driven piston for actuating it, a mechanically driven reciprocating piston mechanically independent of the said air driven piston and adapted to retract it on its return stroke, a cylindrical shell within which said pistons have a sliding fit, connections whereby the mechanically driven piston compresses air on its forward stroke, and valve-controlled ducts for leading the compressed air to the rear of the bit actuating piston. 30
7. The combination with a drill, of a drill frame or casing, a motor and detachable legs for joining the motor to the drill casing, 35 substantially as set forth. 40
8. The combination with a drilling device, of a driving mechanism, a sliding block connection between the said drilling device and the said driving mechanism, and means substantially as described for adjusting the block. 45
9. The combination in a drilling mechanism with the reciprocating parts, a crank driving device therefor, of a sliding block or head 35, a guide therefor, wedge-like parts for adjusting the guide, and means for adjusting the wedge-like parts, substantially as set forth. 50
10. The combination with a drill, of means for compressing air and applying the pressure to said drill, a valve controlling the intake to the compressing mechanism and means operated by the pressure applied to the drill for opening said valve. 55
- 60 11. The combination with a drill, of means for compressing the air and applying the pressure to said drill, of a valve controlling the intake to the compressing mechanism, means subjected to the pressure applied to said drill, for opening said valve, and a sec-
- ond valve controlling the flow of air from the compressing mechanism to the point of application to the drill, said valves opening into the same chamber so that when the intake valve is open the other of said valves is closed, and means for adjusting said valves. 70
12. The combination with a guide frame, of a drill body, said body and frame being detachably connected at the forward end of said frame and a clamping device securing the rear end of said frame to said body. 75
13. The combination of a relatively stationary cylinder, a piston reciprocable therein, power means for reciprocating the same, a second piston reciprocable within the said cylinder between the first mentioned piston and the rear head of the cylinder and normally separated from said piston and rear head longitudinally by air chambers, means for maintaining relatively high air pressure in the said air chambers, and tool-operating means connected with the second piston for applying power to the cutting tool, the parts being shaped to provide restricted communication between the air chambers in front and to the rear of the second piston. 80
14. The combination of a relatively stationary cylinder, a piston reciprocable therein, power means for reciprocating the piston, a second piston longitudinally movable with respect to the first piston, disposed between the said first piston and the rear head of the cylinder so as to provide air chambers between it, and the said rear head and said first piston, respectively, and being provided with connections for applying power to the cutting tool, means for maintaining relatively high air pressure in the said air chambers, the parts being shaped to provide an air-tight chamber between the two pistons when relatively close to each other longitudinally and to provide restricted communication between the two air chambers upon the two sides of the second piston when the two pistons occupy other relative positions longitudinally. 95
15. The combination of a cylinder, two co-axially arranged pistons reciprocable therein, and mechanically free to move longitudinally with respect to each other, one of the said pistons being power-driven, ducts and valves adapted in connection with the power-driven piston to provide air pressure to operate the second piston, and means connected with the second piston adapted to apply power to the cutting tool, the power-driven piston being between the cutting tool and the second piston. 110
16. The combination of a cylinder, a motor, a piston reciprocable within the cylinder, a cross-head rigidly connected to the piston, power transmitting gearing connecting the motor with the cross-head, and a second tool-operating piston longitudinally movable with respect to the first piston and 125
- 130

positioned at all times between the first piston and the cross-head.

17. The combination of a motor, a relatively stationary cylinder having a single straight longitudinal axis, a piston reciprocating therein, power transmitting gearing connecting the motor and the piston and adapted to reciprocate the latter, a second piston longitudinally movable with respect to the first piston, reciprocable within the said cylinder and located at the rear of the first piston, and valve mechanism and connections whereby the first piston compresses air upon its forward stroke, the second piston being driven forward by the air thus put under pressure to apply power to the cutting tool, and retracted by the action of the simultaneously retracted first piston.

18. The combination of a motor, a relatively stationary cylinder, a piston mechanically reciprocated within the said cylinder by means of the motor, a second piston longitudinally movable with respect to the first piston and reciprocable within the same cylinder between the first piston and the rear cylinder head, means for applying air pressure to the second piston to move it on its outward stroke, the first piston being adapted to alternately permit such forward movement of the second piston and to retract the second piston as it is reciprocated by the said motor.

19. The combination of a motor, a relatively stationary cylinder, a piston mechanically reciprocated within the said cylinder by means of the motor, a second piston longitudinally movable with respect to the first piston and reciprocable within the same cylinder between the first piston and the rear cylinder head, means for applying air pressure to the second piston to move it on its outward stroke, the first piston being adapted to alternately permit such forward move-

ment of the second piston and to retract the second piston as it is reciprocated by the said motor; the pistons and cylinder being adapted to maintain an air-tight space between the two pistons during such retractions.

20. The combination of a motor, a relatively stationary cylinder, a piston mechanically reciprocated within the cylinder by means of the motor, air ducts and valves whereby the piston acts to compress air upon its forward stroke, a second piston arranged between the first piston and the rear head of the cylinder and reciprocable therein, means for maintaining an air cushion between the two pistons and means for conducting the air compressed by the first piston upon its forward stroke to the rear of the second piston, whereby the second piston is constantly under air pressure tending to move it forward and is retracted periodically by the greater air pressure of the air cushion between the two pistons when the first piston is being mechanically withdrawn.

21. The combination of a tool actuating piston, a cylinder within which it is reciprocable, means for maintaining air pressure upon the rear face of the piston, and a power reciprocated part operatively connected at all times during both reciprocations to an engine or motor and arranged when moving rearward to retract the said piston against the said air pressure, and when moving forward to permit the said air pressure to cause the tool-actuating piston to move forward and follow the said part.

In testimony whereof I affix my signature in presence of two witnesses.

SAMUEL S. WYER.
